ATTORNEY

UNITED STATES PATENT OFFICE

ALBERT E. GRANT, OF NEW YORK, N. Y., ASSIGNOR TO GRANT HEAT MACHINE CORPORATION, OF NEW YORK, N. Y., A CORPORATION OF DELAWARE

OIL BURNER

Application filed February 11, 1928. Serial No. 253,580.

My invention relates to oil burners and the object of my invention is to provide a practical device of simple construction adapted for burning oil by vaporizing the same without 5 the necessity of first atomizing it.

A further object is to provide a device for this purpose embodying a plurality of burners arranged for separate or joint use and formed integral and adjacent to each other so 10 that one of the burners may serve as a pilot light for the other burner.

The novel features are set forth in the following specification:—

The drawing shows a burner embodying 15 my invention, connected in operative relation to an oil feeding device and air pump construction for the purpose of illustrating the operation of the burners forming the subject matter of this application. The burner 20 is shown in a longitudinal sectional view, and comprises a casing A, adapted to be connected to the casing of an air conduit B, thru which air may be supplied from an air blower or pump C, and the casing A is also provided 25 with conduits D and D¹ respectively, in open communication with oil supply pipes D² and D³ respectively, which conduct oil from separate oil chambers E and E¹ in which oil is maintained at predetermined levels, and 30 whereby oil is maintained at a corresponding level in the oil chambers of the burners. Formed in the casing A is a chamber A¹ having an inlet passage B¹ in open communication with the air conduit B to which it is held 35 by means of the nut and rod construction B² as illustrated.

The upper end of the casing A is provided with an annular circular chamber A² which is in open communication with the chamber 40 A¹ by air passages A³—A³ respectively.

The casing A is provided with a tubular portion A having a smaller annular chamber F formed therein in which is located a cylindrical wick F¹ of porous refractory material freely removable therefrom after a central spreader G is first removed. The spreader G rests in a central bore G¹ formed in the central tubular portion H of the casing A and supported by vertically extending ribs H¹ 45 formed integral therewith. An air deflecting

collar I, shaped substantially as shown, is also supported by the central tubular portion H, to deflect air downward into the chamber A². The top of the burner comprises a ring J, formed in a separate casting to permit of 55 easy moulding of the casing A and provides an annular passage K, for the gaseous fuel formed by the mixture of air passing thru the chamber A² when mixed with the hydrocarbon gas generated by heating the oil in said 60 chamber.

When the several parts are assembled as shown and the oil is maintained at the level indicated in the chamber A² and at a level in the chamber F at a point just below the top 65 of the wick F, the oil is ignited by a flame applied to the top of the wick. Air received from the blower flows thru the casing A upward thru the central passage to supply the central burner which soon becomes hot enough 70 to heat the entire casing and the oil in the large burner then is converted into gas which flows upward thru the annular passage K. The air also flows thru the passages A³ and is deflected thru the chamber A² and mixed 75 with the gas, generated therein, and the mixture is ignited by the small burner referred to as the Pilot burner. Proper automatic means are provided for use with this burner whereby the oil may be shut off from the large 80 burner comprising chamber A² which means form the subject matter of a separate application for patent, and are therefore not shown or described herein. A burner constructed in accordance with the drawings built twice 85 the size of the illustration has been built and operated in a very satisfactory manner.

Having thus described my invention I claim as new:—

1. In combination, two independent oil 90 burners located adjacent to each other and adapted to be operated separately or simultaneously, an air chamber and conduits for air leading therefrom to each of said burners, said burners comprising annular chambers 95 for oil, one of which is open and exposed at its upper end directly to the atmosphere, and means for deflecting air from said air chamber downwardly into said open annular oil chamber to provide a fuel mixture. 100

2. In combination, two independent oil burners comprising an outer annular open chamber for oil and a separate burner located adjacent thereto and adapted to serve as a pilot light for said outer burner, and means for leading air and oil to supply each of said burners separately, and a spreader for said separate burner to deflect air thereover as set forth.

10 In testimony whereof I have affixed my signature.

ALBERT E. GRANT.
